UNITED STATES PATENT OFFICE.

FERD S. BARBIERS, OF LANCASTER, OHIO, ASSIGNOR TO THE HOCKING GLASS COMPANY, OF LANCASTER, OHIO, A CORPORATION OF OHIO.

DESIGN FOR A LIGHT-GLOBE.

51,130.

Specification for Design.

Patented Aug. 14, 1917.

Application filed May 25, 1917. Serial No. 171,033. Term of patent 7 years.

To all whom it may concern:

Be it known that I, FERD S. BARBIERS, a citizen of the United States, and resident of Lancaster, in the county of Fairfield and State of Ohio, have invented a certain new, original, and ornamental Design for a Light-Globe, of which the following is a specification, reference being had to the accompanying drawing, forming part thereof, in which—

The figure shows a side elevation of a light globe showing my new design.

I claim:—

The ornamental design for a light globe, as shown.

In testimony whereof, I, the said FERD S. BARBIERS, have hereunto set my hand.

FERD S. BARBIERS.

Witnesses:

R. E. LEHMAN,
H. V. FULTON.
